UNITED STATES PATENT OFFICE.

GEORGE PALMER, OF LITTLESTOWN, PENNSYLVANIA.

IMPROVEMENT IN METALLIC GRINDING-MILLS.

Specification forming part of Letters Patent No. 35,036, dated April 22, 1862.

To all whom it may concern:

Be it known that I, GEORGE PALMER, of Littlestown, in the county of Adams and State of Pennsylvania, have invented new and useful Improvements in Metallic Grinding-Mills, and the following is a full, clear, and exact description of the same, reference being had to the accompanying drawings, making a part of this specification, in which—

Figure 1 shows a vertical section of the cylinder grinding-surfaces. Fig. 2 shows the revolving cone with the movable ventilated grinding-slats. Fig. 3 represents an end view or section through the mill at the red line in Fig. 1.

My invention consists in attaching to a revolving cone movable ventilated longitudinal slats in sections to be used in combination with similar concave yielding and adjustable slats attached to the rim or covering.

To enable others skilled in the art to make and use my invention, I will proceed to describe its construction, operation, and effects, referring to the drawings and to the letters marked thereon.

The outside covering and frame, A A, may be made of metal or wood and of as many pieces and such form as desired, they being secured and held together by bolts and flanges or surrounded by hoops, the diameter of the base or large end being about one-third larger than the other.

Inside of the concave covering A A are recesses a a a a, six or eight in number, into which are fitted longitudinal concave grinding-plates B B B B, to be made of chilled cast-iron or tempered steel. These plates are made of such width and curve as to about fill the circle at the large ends b b b b. At about one-third of the distance from the large end is an offset, leaving a space and recess, c, between the narrow ends of the grinding-plates B B B B.

Between the covering A A and the concave plates B B is left at the large end a space, d d d, to allow the plates to yield back and the circle formed by the plates B B to expand when any extraneous substance comes in contact with them that cannot be crushed. The plates B B are held up to the work by springs e e e e, placed between them and the covering A A, which are adjustable by the action of

set-screws f f f, so that any amount of pressure may be applied that is necessary to grind or pulverize various substances.

The revolving cylinder D may be made of wood or metal placed upon a shaft, G, the body being conical, so that the sides will be parallel with the concave covering A.

In the surface of the cylinder D are a series of recesses, h h h h, made dovetailed, into which are fitted convex grinding-plates E E E, made of chilled cast-iron or tempered steel of similar construction to the concave plates B B, having offsets and spaces between them at the smallest end, where the material is fed in to be ground. The plates F F have a groove, i i i i, on the under side, so that there is an air-passage the whole length between them and the body of the cylinder D, so that a free current of air is admitted, which has a tendency to keep the plates from heating by friction.

A cylinder constructed as above described has many advantages over any that has yet come to my knowledge. The grinding-plates, being made thin and light, can be made very hard, so that they will wear much longer than those cast in a solid form. Should they become dull and cease to operate fast and well, or get broken, they can easily be removed and others substituted in their places. One pattern answers to make the whole series for a cylinder, and a supply of extra plates may be obtained at any time. The same advantages are also derived by the construction and mode of inserting the stationary plates B in the cover, so that they can easily be removed and others put in their places; but a very great advantage is found in having them separate and so that they can yield to allow the passage through of such substances as are not readily crushed; and, again, they being made adjustable by set-screws, can be regulated to act with certainty on all varieties of grain and other material for which mills are used.

My improved metallic grinding-mill may be placed in any desired position—either vertical, inclined, or horizontal—and works in a most satisfactory manner. The journals of the shaft G may run in boxes or have a step and regulating screw or lever in the same manner as ordinary mills of like character. They may be run with much greater speed than other metallic mills, and will conse-

quently grind more stuff in a given time. They may be driven by a belt and pulley or gear-wheels and used by horse, water, or steam power with the most satisfactory results. In short, their superior is not found to exist.

Having thus fully described my improved grinding-mill, what I claim as my invention, and desire to secure by Letters Patent, is—

The movable ventilated longitudinal grinding-plates attached to a revolving cylinder in

sections, in the manner herein described, in combination with the concave grinding-plates secured to the covering and made yielding and adjustable by springs and set-screws or their equivalents, in the manner as and for the purposes herein set forth.

GEORGE PALMER.
